Primary Examiner — Paula Allen Greene(57) **CLAIM**

The ornamental design for an urn pedestal for funeral vehicle as shown and described.

DESCRIPTION

FIG. 1 is a front right perspective view of an urn pedestal for funeral vehicle showing our new design;

FIG. 2 is a front right perspective view of the urn pedestal for funeral of FIG. 7;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken and dashed lines depict portions of the urn pedestal for a funeral vehicle that form no part of the claimed design.
